J. F. KIDDER

CORNICE BRAKE

Filed April 19, 1921

FIG. 2.

By *John F. Kidder* Attorney

UNITED STATES PATENT OFFICE.

JOHN F. KIDDER, OF BURLINGTON, VERMONT.

CORNICE BRAKE.

Application filed April 19, 1921. Serial No. 462,691.

To all whom it may concern:

Be it known that I, JOHN F. KIDDER, a citizen of the United States, residing at Burlington, in the county of Chittenden and 5 State of Vermont, have invented certain new and useful Improvements in Cornice Brakes, of which the following is a specification, reference being had therein to the accompanying drawing.

10 This invention relates to certain new and useful improvements in cornice brakes for bending sheet metal and the like, the object being to provide novel means of mounting and operating the movable jaw of the brake 15 so that the same can be adjusted to a nicety in order to enable the same to be set for working on different thicknesses of metal.

Another and further object of the invention is to provide a novel form of double 20 eccentric mounted within the connecting link, one of the eccentrics being adjustably mounted within the link so as to set the movable jaw in the desired position in respect to the fixed jaw.

25 Other and further objects and advantages of the invention will be hereinafter set forth and the novel features thereof defined by the appended claim.

In the drawings, 30 Figure 1 is a side elevation of the upper portion of an ordinary form of cornice brake showing the application of my improved construction of double eccentric; and

Fig. 2 is a section taken on line 2—2 of 35 Fig. 1.

In the drawings 1 indicates a bed forming the fixed jaw of the cornice brake which has adjustably mounted thereon a bracket 2 in which is loosely mounted a movable 40 jaw 3. Pivotaly mounted on the bed 1 is a link 4 which is split as shown at 5 and is provided with apertured ears 6 and 7, the apertured ear 7 being threaded to receive a bolt 8 clamping the ears together for the 45 purpose hereinafter fully described.

The link 4 is provided with a circular opening 9, the wall of which is grooved, the groove being struck on the arc of a circle to form a concave face 10 in which is ar- 50 ranged an eccentric 11 having its peripheral wall formed with a convexed face 12 corresponding to the curvature of the groove.

The eccentric 11 is provided with a span- 55 ner receiving opening 13 in which a spanner is adapted to be placed for turning the eccentric within the connecting link 4, it of

course, being understood that the bolt 8 is first loosened. Mounted within the eccentric 11 is an eccentric 14, said eccentric working over a stud 15 carried by the movable jaw 3 and provided with a handle 16 for operating the same so as to move the movable jaw of the brake towards and away from the fixed jaw.

The operation of the invention when applied to a cornice brake as herein shown is as follows:—Assuming that it is desired to work on material of a certain thickness, the bolt 8 is loosened and a spanner wrench placed in the openings of the eccentric 11 and the eccentric is adjusted within the link 4 so as to set the movable jaw a predetermined distance away from the fixed jaw of the brake, the bolt 8 being then tightened so as to lock the jaw in its adjusted position.

The material is then placed between the jaws in the ordinary manner and by operating the handle 16, the movable jaw is forced into engagement with the material so as to securely clamp the same between the jaws.

From the foregoing description it will be seen that I have provided a cornice brake with a double eccentric for adjusting and operating the movable jaw of the brake which enables the movable jaw to be predeterminedly set so that it will be held the desired distance away from the fixed jaw.

While I have shown certain details of construction of a cornice brake, I do not wish to limit the use of my double eccentric to any particular construction of cornice brake as I am aware that the same can be used in connection with various forms of metal bending machines and my invention consists broadly in providing a metal bending machine having a movable jaw operated by an eccentric mounted within an adjustably mounted eccentric for allowing the movable jaw to be predeterminedly set so that it will be held the desired distance away from the fixed jaw which enables the machine to be adjusted to operate on various thicknesses of material so as to save time in the operation of the machine.

What I claim is:—

A cornice brake having a bed forming a fixed jaw, an adjustable support carried by said jaw, a movable jaw mounted in said support, said movable jaw being provided with a laterally extending stud pin at one end, a link 110 pivotally connected to the fixed jaw below said movable jaw and extending upwardly op-

posite said movable jaw, said link having an opening provided with a concave wall forming an annular groove and provided with a split portion provided with laterally extending ears, a bolt connecting said ears together, an adjustable eccentric arranged within the opening of said link having a peripheral wall corresponding in shape to the wall of said opening, said eccentric hav-

ing an opening to receive a second eccentric, 10 the last mentioned eccentric being provided with an opening to receive said stud pin and a handle carried by the last mentioned eccentric for operating said movable jaw.

In testimony whereof I hereunto affix my 15

JOHN F. KIDDER.
